(57) **CLAIM**

The ornamental design for a product with suspended pieces, as shown and described.

DESCRIPTION

The product with suspended pieces shows a product with suspended quadrangular shaped pieces.

FIG. 1 is a perspective view of the product with suspended pieces of my design ;

FIG. 2 is a front elevation view thereof.

FIG. 3 is a rear elevation view thereof.

FIG. 4 is a right side elevation view thereof.

FIG. 5 is a left side elevation view thereof.

FIG. 6 is a top plan view thereof; and,

FIG. 7 is a bottom plan view thereof.

The broken line showing of a container is for illustrative purposes only and forms no part of the claimed design.
